PAIN RELIEF APPLIANCE

Caron Sarnoff, 3206 Corinth,
Los Angeles, Calif. 90066

Filed July 24, 1972, Ser. No. 274,410

Term of patent 14 years

Int. Cl. D24—04

U.S. Cl. D83—1 K

Fig. 1.

Fig. 2.

Fig. 3.

Fig. 4.

Fig. 5.

Fig. 6.

FIG. 1 is a front view of my pain relief appliance showing it in use;

FIG. 2 is a side view of my pain relief appliance shown in FIG. 1;

FIG. 3 is a plan view of my pain relief appliance, depicting it in the non-use, unapplied state;

FIG. 4 is a view taken along the line 4—4 of FIG. 3;

FIG. 5 is a view taken along the line 5—5 of FIG. 3; and

FIG. 6 is a view taken along the line 6—6 of FIG. 3. The broken lines are shown for illustrative purposes only.

I claim:

The ornamental design for a pain relief appliance, as shown and described.
